[57] **ABSTRACT**

A radio frequency attenuator including a ladder network made up of "N" serially coupled stages, each one of such stages having an output terminal coupled to a radio frequency source through a first and a second path, such second path having disposed therein a variable phase shifter. Included in each such stage is a load adapted to dissipate in the order of one Nth the power in the radio frequency energy. Each one of the phase shifters is responsive to a binary signal and the phase shift provided by each one of such phase shifters changes M 180° in accordance with the binary signal (where M is an odd integer).

**RADIO FREQUENCY ATTENUATOR COMPRISING
A PLURALITY OF VARIABLE PHASE SHIFTERS
AND SERIALLY COUPLED DIRECTIONAL
COUPLERS**

BACKGROUND OF THE INVENTION

This invention relates generally to radio frequency attenuators and more particularly to high power variable radio frequency attenuators.

As is known in the art, radio frequency (R.F.) digitally controlled attenuators such as the type described in U.S. Pat. No. 3,765,020, inventors Seager et al., issued Oct. 9, 1973 and assigned to the same assignee as the present invention, include a ladder network wherein switching elements, each one responsive to digital signals, are selectively actuated to connect radio frequency energy desired to be attenuated to a load in such network. With means for equalizing the phase of radio frequency energy passing through the various paths possible in such a ladder network, it is possible then to control the attenuation of radio frequency energy by selectively actuating the switching elements. While attenuators of the just-mentioned type have been found to be adequate for many purposes, there are many applications where their use is not feasible at the present time. For example, if the radio frequency energy to be attenuated is at a relatively large power level, say in the order of several megawatts, each one of the switching elements should, to avoid the possibility of damage from overloading, be capable of switching radio frequency energy at a power level at least equal to the power level of the radio frequency energy to be attenuated. Therefore, while in theory it would be possible to provide switching elements having the requisite capacity to switch radio frequency energy at any given power level, the present state of the development of switching elements dictates that, if radio frequency energy at a high power level is to be attenuated, the use of an attenuator of the just-mentioned type is not practical.

SUMMARY OF THE INVENTION

With this background of the invention in mind, it is an object of this invention to provide an improved variable attenuator for radio frequency energy having a power level up to several megawatts.

This and other objects of the invention are attained generally by providing a ladder network made up of "N" serially coupled stages for attenuating radio frequency energy, each one of such stages being adapted to dissipate in the order of one Nth of the power of such energy. To accomplish such end, each stage includes: A pair of input terminals; a pair of output terminals; a load; an adjustable phase shifter responsive to a control signal; and, a pair of directional couplers. The directional couplers each have one input coupled to a different one of the pair of input terminals, one output coupled to a different one of the pair of output terminals, and a second output, the second output of a first one of the directional couplers being coupled to the load and the second output of a second one of the directional couplers being coupled to a second input of the first one of such directional couplers through the adjustable phase shifter. In a preferred embodiment one of the output terminals of each of the stages is coupled to an R.F. source through a first path and a second path, such second path having disposed therein the variable phase

shifter. Such phase shifter is responsive to a binary signal and the phase shift provided by such phase shifter changes M 180° in accordance with the binary signal (where M is an odd integer).

5 BRIEF DESCRIPTION OF THE DRAWING

Other objects and advantages of this invention will become apparent from the foregoing specification taken in connection with the accompanying single FIG-

10 URE which shows a variable radio frequency attenuator in accordance with the invention.

**15 DESCRIPTION OF THE PREFERRED
EMBODIMENT**

Referring now to the FIGURE, a radio frequency source 10 (here producing a radio frequency signal of several megawatts power and a frequency of several megahertz) is shown coupled to a load 12 through an N stage digitally controlled radio frequency attenuator 14. Such radio frequency attenuator 14, the details of which will be described below, is adapted to attenuate the radio frequency energy supplied by the source 10 with a selected one of 2^N attenuating factors ranging from 0.0 to 1.0, such factors being selected by a conventional digital computer 16.

20 Radio frequency attenuator 14 includes a 3 db coupler, here a conventional hybrid junction 16, having an H-arm 18 coupled to the radio frequency source, an E-arm 20 coupled to a suitable load 22, and a pair of side arms 24, 26. The side arms 24, 26 are connected, here by waveguide, to the first one of the N serially coupled stages 27₁ to 27_N.

25 Each one of the first N-1 stages 27₁ to 27_{N-1} includes

30 a pair of directional couplers: 30₁, 32₁; . . . 30_{N-1}, 32_{N-1}; as shown. The Nth stage 27_N includes a single directional coupler 30_N, as shown. Each one of the directional couplers 30₁ to 30_N and 32₁ to 32_{N-1} is of conventional design and includes a pair of input ports i_1 , i_2 and a pair of output ports o_1 , o_2 . Directional couplers 30₁ to 30_N are serially coupled by the waveguide connecting the output port o_1 of one of the couplers to the input port i_1 of the adjacent one of such couplers. Likewise, directional couplers 32₁ to 32_{N-1} are serially coupled by waveguide connecting the output port o_1 of one of the couplers to input port i_1 of the adjacent one of such couplers. The output port o_1 of the directional coupler 30_N is coupled to the load 12. As is known, radio frequency energy introduced into input ports i_1 and i_2 is coupled to output ports o_1 , o_2 in accordance with the following relationship as described in detail in the article "On the Design of Optimum Dual-Series Feed Networks" by Jones et al., Transactions on Microwave Theory and Techniques, Volume MTT-19, No. 5, May, 1971, pgs. 451, 453:

$$V_{o_1} = V_{i_1} \cosine \theta + jV_{i_2} \sin \theta \quad (1)$$

$$V_{o_2} = jV_{i_1} \sin \theta + V_{i_2} \cosine \theta \quad (2)$$

where:

35 V_{o_1} = the voltage produced at the output port o_1

V_{o_2} = the voltage produced at the output port o_2

40 V_{i_1} = the voltage introduced into input port V_{i_1}

V_{i_2} = the voltage introduced at input port V_{i_2}

45 θ is the coupling index of the directional coupler and $j = \sqrt{-1}$.

50 The output port o_2 of each one of the directional couplers 30₁ to 30_N is coupled to a different load (i.e. loads 38₁ to 38_N) as shown. Such loads 38₁ to 38_N are here designed, for reasons to be apparent, to handle 1/Nth the power supplied by the radio frequency source 10. The

input ports i_2 of directional couplers 32_1 to 32_{N-1} are coupled to a different load, i.e. matching impedances 40_1 to 40_N (as shown). Matching impedances 40_1 to 40_{N-1} are designed to handle a lower amount of power than $1/N$ th the power supplied by the source 10 because each simply provides conventional impedance matching.

Also included in the first $N-1$ stages are switchable phase shifters 42_1 to 42_{N-1} , such phase shifters being coupled between the input ports i_2 of directional couplers 30_1 to 30_{N-1} and the output ports o_2 of directional couplers 32_1 to 32_{N-1} as shown in the FIGURE. The N th stage 27_N includes a switchable phase shifter 42_N coupled between the output port o_1 of directional coupler 32_{N-1} and the input port i_2 of directional coupler 30_N . The switchable phase shifters 42_1 to 42_N are coupled respectively, by way of control lines 44_1 to 44_N , to the digital computer 16 . Such switchable phase shifters 42_1 to 42_N are of any conventional design to change the radio frequency energy passing therethrough 180° in response to a change in the binary signal on the control line coupled thereto.

It is here noted that the radio frequency digitally controlled attenuator 14 is constructed so that: When the switchable phase shifter in any one of the stages, say stage 27_m , is in state 0 (i.e. provides 0° phase shift to the radio frequency signals passing therethrough) the electrical length, via side arm 24 , from H-arm 18 to the output port o_1 of the directional coupler 30_m of such stage differs from the electrical length, via side arm 26 , from such H-arm to such output port o_1 by $M\lambda/2$ (where M is an odd integer and λ is the nominal operating wavelength of the radio frequency energy applied to the attenuator) and; when the switchable phase shifters are in state 1 (i.e. provides 180° phase shift to the radio frequency energy passing therethrough) the electrical lengths referred to above differ by $M\lambda$. Such requirements may be achieved by proper waveguide length selection and/or by using conventional line stretchers (not shown). It follows then, assuming the directional couplers to be ideal lossless devices, that by proper selection of the coupling index, θ , for each one of the directional couplers: (a) When all of the switchable phase shifters are in the state 0 condition, the radio frequency energy applied to the hybrid junction 16 may be distributed equally between the loads 38_1 to 38_N ; (b) When all of the switchable phase shifters are all in the 1 state, all of the radio frequency energy from the source is transferred to the load 12 ; and (c) Finally, each different one of the 2^N combination of states of the switchable phase shifters causes the radio frequency energy to be divided between the load 12 and some of the loads 38_1 to 38_N . In other words the state of the individual ones of the switchable phase shifters may be changed to vary the attenuation of radio frequency energy passed through the illustrated attenuator.

In order to more completely understand the attenuator, and more particularly the derivation of the coupling indices of the directional couplers, let us consider the following: When all of the stages are in the state 1 condition, the relationship between input voltages and output voltages of any one of the stages, say stage 27_m , may be represented as follows:

$$V_{i_1}^{(0)} = V_{i_1}^{(1)} \cos \theta_1 + V_{i_2}^{(1)} \sin \theta_1 \sin \theta_2 \quad (3)$$

$$V_{o_2}^{(0)} = j[V_{i_1}^{(1)} \sin \theta_1 - V_{i_2}^{(1)} \sin \theta_2 \cos \theta_1] \quad (4)$$

$$V_{o_3}^{(0)} = V_{i_2}^{(1)} \cos \theta_2 \quad (5)$$

where:

V_{i_1} = voltage on terminal i_1 of directional coupler 30_m

V_{i_2} = voltage on terminal i_1 of directional coupler 32_m
 V_{o_1} = voltage on terminal o_1 of directional coupler 30_m
 V_{o_2} = voltage on terminal o_2 of directional coupler 30_m
 V_{o_3} = voltage on terminal o_1 of directional coupler 32_m ; and,

θ_1 = coupling index for directional coupler 30_m

θ_2 = coupling index for directional coupler 32_m

(superscript (1) indicates state 1)

When all of the stages are in the state 0 condition, the following relationships may be represented:

$$V_{i_1}^{(0)} = V_{i_1}^{(1)} \cos \theta - V_{i_2} \sin \theta_1 \sin \theta_2 \quad (6)$$

$$V_{o_2}^{(0)} = j[V_{i_1}^{(1)} \sin \theta_1 + V_{i_2} \sin \theta_2 \cos \theta_1] \quad (7)$$

$$V_{o_3}^{(0)} = V_{i_2} \cos \theta_2 \quad (8)$$

(superscript (0) indicates state 0)

Because when all of the stages are in the state 1 condition $V_{o_2}^{(1)} = 0$, then (from Eq. 4)

$$V_{i_1}^{(1)} \sin \theta_1 = V_{i_2} \sin \theta_2 \cos \theta_1 \quad (9)$$

or

$$\sin \theta_2 = [V_{i_1}^{(1)} / V_{i_2}] \tan \theta_1 \quad (10)$$

Because when all of the stages are in the state 0 condition $V_{o_2}^{(0)} = K^2 V_T^2$ (where: V_T is the voltage of the signal applied to the attenuator; $K = 1/N$; and, N = the number of stages), then

$$V_T^2 K^2 = V_{i_1}^{(0)2} \sin^2 \theta_1 + (2V_{i_1}^{(0)} V_{i_2} \sin \theta_1 \cos \theta_1 \sin \theta_2) + V_{i_2}^{(0)2} \sin^2 \theta_2 \cos^2 \theta_1 \quad (11)$$

Therefore,

$$V_T^2 K^2 = [\sin^2 \theta_1] [V_{i_1}^{(0)} + V_{i_2}^{(0)}]^2 \quad (12)$$

or

$$\theta_1 = \sin^{-1} KV_T / (V_{i_1}^{(0)} + V_{i_2}^{(0)}) \quad (13)$$

Let us consider for purposes of example of 10 stage attenuator assuming it to have lossless phase shifters and couplers.

Therefore, from the above equation, for stage 27_1 ,

$$V_T^2 K^2 = .1 V_T^2; \text{ and, } V_{i_1}^{(0)} = V_{i_2}^{(0)} = V_T / \sqrt{2}$$

$$\theta_1 = \sin^{-1} (\sqrt{.1} V_T) / (2V_T - \sqrt{2}) = \sin^{-1} (0.05) =$$

$$12.92^\circ$$

$$\theta_2 = \tan^{-1} [\sin^{-1}(0.223)] = 13.25^\circ$$

For succeeding stages:

	θ_1 (deg.)	θ_2 (deg.)
stage 27_2	13.27	14.38
27_3	13.64	15.74
27_4	14.04	17.4
27_5	14.48	19.48
27_6	14.96	22.21
27_7	15.50	26.01
27_8	16.12	31.86
27_9	16.78	42.42
27_{10}	17.58	—

It should be noted that, as is known, the above coupling indices would be adjusted in accordance with the losses in the directional couplers and phase shifters.

While the described embodiments of the invention are useful to an understanding thereof, it will be immediately apparent to those having ordinary skill in the art that other embodiments are also covered by the inventive concepts disclosed herein. It is felt, therefore, that the invention should not be restricted to its disclosed embodiments but rather should be limited only by the spirit and scope of the following claims.

What is claimed is:

1. A radio frequency attenuator for coupling a source of radio frequency energy to an output load with an amount of attenuation selected in accordance with signals provided by a control signal source, comprising:
  - a first plurality of serially coupled directional couplers, the last one thereof being adapted for coupling to the output load;
  - a plurality of loads, each one thereof being coupled to a different one of the directional couplers;

- c. a plurality of variable phase shifters, each one thereof being coupled to a different one of the directional couplers and to the control signal source;
- d. a second plurality of directional couplers, each one thereof being coupled to a different one of the first plurality of directional couplers through a different one of the variable phase shifters; and
- e. a power divider having an input terminal adapted for coupling to the source of radio frequency energy, and a pair of output terminals, one of such output terminals being coupled to the first one of the first plurality of serially coupled directional couplers and the other one of the pair of output terminals being coupled to

the first one of the second plurality of serially coupled directional couplers.

2. The radio frequency attenuator recited in claim 1 wherein each one of the directional couplers in the first plurality thereof is coupled to the pair of output terminals of the power divider through two paths, one of such two paths having one of the phase shifters disposed therein, and wherein the control signal source is adapted to set the one of the phase shifters in a selected one of two phase states, one of such phase states providing $M(180^\circ)$ (where M is an odd integer) phase shift to radio frequency energy passing therethrough relative to the phase shift provided to such energy when such phase shifter is set in the other one of such phase states.
